PAUL YOHNS, OF NEW YORK, N. Y.

PATTERN-TRANSFER MACHINE.

1,421,884.

Specification of Letters Patent.

Patented July 4, 1922.

Application filed July 19, 1919. Serial No. 312,089.

To all whom it may concern:

Be it known that I, PAUL YOHNS, a citizen of Germany, and a resident of the city of New York, borough of Manhattan, in the 5 county and State of New York, have invented a new and Improved Pattern-Transfer Machine, of which the following is a full, clear, and exact description.

This invention relates to a pattern-trans- 10 fer machine, and aims to provide a machine of this nature by means of which patterns, such as embroidery patterns, may be transferred from a master pattern to those patterns used by needle workers, in a more effi- 15 cient and economical manner.

It is well known in connection with embroidery patterns which are placed face down upon cloth and a hot iron, or other suitable instrument, run over the back of 20 the same, which results in the transfer of the imprint upon the face of the cloth, that the greatest reason for the expense in connection with them is the method of using expensive copper cylinders on the surface of 25 which the design is engraved by hand and from which the so engraved design is printed on to the paper in the ordinary rotary way.

In view of the above, I have constructed 30 a machine which does not use an engraved copper cylinder to print upon the paper, but instead a master pattern made out of tracing linen, or even a fiber sheet, is utilized, through which the design to be printed is 35 perforated with a perforating machine of well-known construction.

Another object of the invention is, as briefly brought out, the provision of a machine by means of which it will be possible 40 to turn out transfer patterns at a much faster rate of speed, in that it has heretofore been impossible to commercially make transfer patterns from a sheet of tracing linen or paper.

A still further object is the provision of 45 a soft bed of material which will enable the master pattern to be utilized a maximum number of times without becoming in the slightest damaged.

A further object of my invention is the incorporation in a machine of the above

character of certain structure which will permit the thickness of the dotted lines to be varied at will.

Reference is had to the attached three 55 sheets of drawings which illustrate one practical embodiment of my invention, and in which—

Figure 1 is a sectional side view of my improved device; 60

Fig. 2 is a sectional plan view thereof; Fig. 3 is an enlarged detail view of the construction whereby adjustment of certain parts of the machine may be effected;

Fig. 4 is a plan view, partly in section, of 65 the structure illustrated in Fig. 3; and

Fig. 5 is an enlarged sectional view through my device illustrating a tension roll employed in connection therewith.

Fig. 6 discloses an enlarged exaggerated 70 construction of the master pattern.

In all of these views, like reference numerals designate similar parts and the reference numeral 1 indicates a casing, which may be provided with inlet and outlet slots 75 2 and 3.

Any suitable source of power (not shown) may be employed, which serves to impart motion to driving belts or other suitable power-transmission structure, as indicated 80 by the reference numerals 4 and 5. A belt 5 passes over a pulley 6 which is keyed to a shaft passing through the interior of the casing 1 and upon which is mounted a drum 7. Adjacent both ends of the shaft there is 85 mounted upon the same a gear wheel 8 which meshes with gears 9, in turn meshing with gears 10, which serve to impart to the drum 12, by means of engagement with the gear 11, rotational movement accurately synchro- 90 nized with respect to the drum 7.

A further drum 13 is mounted upon a shaft adjacent the opposite end of the casing from that in which the drums 7 and 12 are situated, and intermediate the drums 12 and 95 13 there is positioned a trough 14 which is mounted upon slideways 15 and provided with a handle 16 by means of which it will be possible to withdraw such trough from within the casing 1. Rotatably mounted 100 within the trough 14 is a further drum 17 which is mounted upon a shaft 18 projecting

through the side walls of the casing and provided with a pulley 19 over which passes the belt 4 for a purpose hereinafter more fully specified.

5 A tension roll 20 is positioned directly below the trough 14 either inside or outside of the casing 1. A master pattern 20' is now passed around the drums 13 and 12, as well as around the roll 20, and has its ends firmly clamped together by means of a holding and pasting device, such as illustrated in Fig. 1, which device includes a pair of pivoted clamping plates 21 which may be moved by means of set screws 22 and a slidable bar 23 operated by means of a screw 24. It will be understood that one of the free ends of the master pattern is placed below one of the plates 21 and the set screw 22 operated so as to hold this end in applied position. The pattern is then threaded through the various parts and around the drum 12 and roll 20, and its opposite end passed around the drum 13 and brought underneath the second clamping plate 21, which is in turn operated by means of the set screw 22 to retain it in applied position. In the usual manner, the ends of the pattern are coated with paste and placed under the bar 23, which is then projected by means of the screw 24 and brought to bear tightly against the joint constructed between the two ends of the pattern, so that the same may be tight in every particular. Subsequent to the pattern drying and forming a tight joint, the clamping plates 21 are released so that a free movement of the pattern may be effected.

It will be appreciated that the pattern will stretch, particularly under the varying temperatures to which it will be subjected, and in view of this I have provided the side walls of the casing 1 with guide slots 25 in which are slidably mounted journals 26 housing the ends of a shaft upon which a roll 27 is mounted. A cord-and-weight attachment 28 acts upon the slidable journal 26 so as to tend to move the same upwardly and, consequently, retain the proper amount of tension upon the pattern 20'. The tension, which is not provided for by the roll 27, is produced by means of the tension roll 20 which is mounted upon a shaft 29 which has its ends journaled within openings provided in the ends of screw-threaded rods 30. Any suitable arrangement for projecting and retracting the rods 30 may be utilized, but for the sake of convenience I have provided a pair of bevel gears 31 formed with an internal screw-threaded opening through which the rods 30 are adapted to pass. Directly above the bevel gears 31 there extends a shaft 32 operated by means of a handle 33. Fixedly mounted upon this shaft are a pair of bevel gears 34 meshing with the gears 31 so that an operation of the handle 33 will cause the rotation of the bevel gears 31 and a conse-

quential projection or retraction of the rods 30 carrying the tension roll 20 around which the pattern 20' passes.

A roll 35 extends across the casing and to one side of the drum 17. An endless piece 70 of felt, or other suitable material, 36 passes around the roll 35 and the drum 7 and bears with its outer face against the outer face of the pattern 20', as clearly shown in Fig. 1.

For a purpose hereinafter more fully specified, certain parts of the device, such as the drums 13, 17 and 12 and the interior of the trough, are heated. This heating may be accomplished by any suitable arrangement, but for the sake of convenience I have illustrated an ordinary steam-heating arrangement by means of which steam may be introduced into the heating system by a pipe 37, from which it flows through any suitable union 38 to the axle 39, which is provided with apertures 40 which serve to distribute the heating fluid to the interior of the drum 13. To prevent condensation by permitting a slight circulation through the drum, I have provided at the opposite end of the axle 39 a small petcock 41 which may be slightly bent to permit the escape of a small amount of fluid. The axle 18 of the drum 17 is similarly apertured, as indicated by the reference numeral 42, as is also the axle 43 of the drum 12, all of these axles being connected with a suitable source of heat so as to warm the drums which they mount. Reference being had to Figs. 1 and 2, it will be noted that a pipe 44 passes around the base of the trough 14 so that the contents of such trough will be heated through engagement with the hot sides of such pipe.

Any suitable mixture 45, such as wax and ink, is placed within the trough 14 and is retained in a fluid state by means of the heating system aforescribed. The drum 17 is driven by the belt 4, and dipping below the surface of the mixture 45 causes a certain amount of such mixture to impinge upon the upper face of the drum, which is preferably constructed of material such as steel. Upon reaching a certain point in the circumference of the drum 17, the fluid mixture is removed from the outer surface of said drum by means of a scraper blade 46 which terminates at a point adjacent the front face of the roll 35 and, consequently, pattern 20'. A regulating blade 47 is mounted directly above the blade 46 and has its outermost edge terminating in a plane approximately parallel to the outer edge of the blade 46, so that the thickness of the fluid passing outwardly over the blade 46 may be varied at the point of contact with the pattern 20'. A second scraper blade 48 is pivotally mounted, as indicated at 49, to the side walls of the trough 14 and is normally swung upwardly into engagement with the inner face of the pattern 20' by 130

means of a rope and associated weight 50, so that the surplus mixture which has been applied to the inner face of the pattern 20' by means of the blade 46 and plate 47 may 5 be removed and guided again into the trough 14 where, due to the heat, it will quickly become fluid again.

It will readily be appreciated that the plate 47, and particularly the blade 46, must 10 be capable of any number of adjustments. For this reason, referring more particularly to the plate 47, I have swingingly mounted the same between a pair of suspending arms 51 extending from the side 15 walls of the casing 1. The adjustment of the arms 51 is secured by means of a pair of set screws 52 bearing against a suitable abutment 53 associated with one of the arms 51. It will be seen that this method of 20 mounting the plate 47 permits such plate to be swung through an arc the center of which is at a point corresponding to the point of pivoting of the arms 51 and the side walls of the casing 1. A second adjustment is provided by means of mounting the 25 plate 47 pivotally to the lower ends of the arms 51, as aforesaid.

The blade 46 is pivotally mounted upon a bar 54, the ends of which are secured to 30 the outer ends of a movable bar 55 which is slotted, as indicated by the reference numeral 56, at a portion approximately intermediate its two extremities, so that by virtue of a headed pin 57 it will be possible for 35 the bar 55 to be rotated around its slotted portion 56 and also to be moved longitudinally with respect to the pin 57. A pair of rollers 58 and 59 extend transversely through the trough 14. Secured to the 40 outer end of the roller 59 is a forked rod 60 engaging a pin 61 secured to a rod 62, the lower end of which is screw-threaded and projects through a pivotally-mounted set nut 63. Secured to the outer end of the 45 roller 58 is a rod 64 to which is pivotally secured, approximately intermediate its extremities, the inner end of a screw-threaded rod 65 projecting through a pivotally-mounted set nut 66. A link 67 extends, as 50 clearly shown in Fig. 3, between the upper end of the rods 64 and 55.

Paper 68, upon which the pattern is to be transferred, enters through the slot 2 in the casing 1 and passes over a rigid bar 69 and 55 subsequently a bar 70 slidably mounted in slots 71 formed in the side walls of the casing, which latter bar serves the purpose of smoothing and applying tension to the paper 68. Subsequently the paper passes around 60 the roller 72 which is adjustably mounted in the casing 1, which roller serves to also regulate the tension upon the strip of felt, or other material, passing around the roll 65 and drum 7.

Referring now more particularly to Fig.

6, it will be seen that the master pattern 20', if made of paper, includes a number of perforations which, upon the outer surface of the pattern, present upwardly and outwardly extending side walls, as indicated 70 by the reference numeral 69. If made of linen, as indicated by the second view of Fig. 6, it will be seen that the master pattern includes perforations the sides of which extend upwardly and inwardly, as indicated 75 by the reference numeral 70.

In operation, assuming that the master roll 20' has been properly placed around the drums 12 and 13 and the tension roll 20, as well as passing around the rolls 27 and 35, 80 and that the plate 47 and blades 46 and 48 have been properly positioned, it will be seen that the paper 68 may be passed over the bar 69, under the bar 70, around the roll 72, and follow the course of travel of the felt 85 strip passing around drum 7 and roll 35 by virtue of the roll 72. The proper tension will have been imparted to the master pattern 20', and the speeding of the felt strip and pattern will have been absolutely synchronized by means of the system of gearing 90 evolved by myself. The ink 45 being in a fluid state, and the drum 17 being revolved by means of a pulley 19, the ink will follow the outer surface of the drum around and 95 pass outwardly around the upper surface of the blade 46, its flow being properly regulated by means of the plate 47; and so against the inner face of the pattern 20' and through the perforations in the same 100 on to the outer face of the paper 68, which is at the point of contact with the pattern and ink provided with a soft bed by means of the felt strip. The surplus ink is now scraped from the inner face of the pattern 105 20' by means of the blade 48, which also serves to force the residue of the ink within the perforations in the pattern, through and on to the paper 68. Subsequently, the pattern, passing over the hot drums 12 and 13, 110 will cause any ink secreted within the perforations of the pattern to be removed therefrom due to the fact that it reduces such ink to a fluid state and causes it to drop out of the pattern. 115

This operation may be repeated indefinitely, and it is to be readily appreciated that the machine may be run at any speed within reason, and it will produce as perfect a reproduction at a fast speed as at a slow 120 speed, although turning out a great deal more work. Further, it will be understood that the plate 47 and blades 46 and 48 respectively may be adjusted in any manner desired so as to obtain the best penetrative 125 effect of the ink through the perforations in the pattern 20'.

It will be understood that by means of my machine it is possible to utilize a conventional linen or paper perforated master pat- 130

tern, costing merely a fraction of the expense involved in connection with the construction of the usual copper cylinder, and which master pattern may be used an indefinite number of times. Further, it will be noted that by virtue of the unique construction of the perforations, as disclosed in Fig. 6, and the soft bed presented to the outwardly projecting side walls of the perforations upon the outer face of the master pattern, the ink will pass through such perforations and be brought firmly into engagement with the upper surface of the paper, so that a distinct and clear pattern will be reproduced upon the same.

It is further to be appreciated that any number of modifications in connection with this device may be resorted to without in the least departing from the scope of my invention.

Having thus described my invention, I desire to claim:

1. A pattern transfer machine comprising a perforated master pattern, rolls supporting the same, and means to maintain the rolls and consequently the master pattern in a heated condition, whereby printing fluid upon lodging in the perforations is heated and caused to flow.

2. A pattern transfer machine comprising a perforated master pattern, rolls supporting the same, means to maintain the rolls and consequently the master pattern in a heated condition, whereby printing fluid upon lodging in the perforations is heated and caused to flow, and means to pass the printing fluid upwardly through the perforated pattern into contact with the material to be printed upon.

3. A pattern transfer machine comprising a perforated master pattern, rolls supporting the same, means to maintain the rolls and consequently the master pattern in a heated condition, whereby printing fluid upon lodging in the perforations is heated and caused to flow, means to pass the printing fluid upwardly through the perforated pattern into contact with the material to be printed upon, and a regulator associated with said fluid passing means.

4. A pattern transfer machine comprising a perforated master pattern, means to feed a printing fluid upwardly through said pattern, a regulating blade extending longitudinally of the feeding means, means whereby the transverse inclination of the blade may be varied, and a scraping blade beneath said pattern for removing surplus printing fluid from the surface of the pattern and

having means whereby the transverse inclination of the same may be varied.

5. A pattern transfer machine comprising a perforated master pattern, means to feed a printing fluid upwardly through said pattern, a regulating blade extending longitudinally of the feeding means, means whereby the transverse inclination of the blade may be varied, a scraping blade beneath said pattern for removing surplus printing fluid from the surface of the pattern and having means whereby the transverse inclination of the same may be varied, and means to maintain the master pattern in a heated condition whereby the printing fluid which lodges in the perforations of the same is caused to flow.

6. A pattern transfer machine comprising a perforated master pattern, means to feed a printing fluid upwardly through said pattern, a regulating blade extending longitudinally of the feeding means, means whereby the transverse inclination of the blade may be varied, a scraping blade beneath said pattern for removing surplus printing fluid from the surface of the pattern and having means whereby the transverse inclination of the same may be varied, means to maintain the master pattern in a heated condition whereby the printing fluid which lodges in the perforations of the same is caused to flow, said feeding means consisting of a roller and blade to scrape the printing fluid from the last named roller and transfer the printing fluid to the master pattern.

7. A pattern transfer machine comprising a pair of rollers, a perforated master pattern trained about said pair of rollers, a trough between said rollers and adapted for the reception of a printing fluid, a distributing roller rotatable within the fluid and adapted to pick up a quantity of the same, a scraping blade arranged adjacent the upper side of the distributing roller and adapted to transfer the printing fluid from the distributing roller to the master pattern, whereby the printing fluid is passed upwardly through the perforations in said pattern, a regulating blade above said scraping blade, and a second scraping blade for removing the surplus printing fluid from the surface of said pattern and returning the surplus fluid to the trough, and means to maintain said rollers and consequently the pattern in a heated condition, whereby the printing fluid which lodges in said perforations is heated and caused to flow.

PAUL YOHNS.
